[57] CLAIM

I claim the ornamental design for a knob, as shown and described.

DESCRIPTION

FIG. 1 is a perspective view of the knob according to a preferred embodiment.

FIG. 2 is a top plan view of the knob.

FIG. 3 is a front elevation view of the knob; and,
FIG. 4 is a bottom plan view of the knob.

The broken lines at the base of the stem represents the bounds of the claim and all others are for illustrative purposes only. None of the broken lines form a part of the claimed design.

The surface(s) or portion(s) of the article not shown in the drawing or described in the specification form(s) no part of the claimed design.

UNITED STATES PATENT AND TRADEMARK OFFICE
CERTIFICATE OF CORRECTION

PATENT NO. : Des. 435,424
DATED : Dec. 26, 2000
INVENTOR(S) : Short

It is certified that error appears in the above-identified patent and that said Letters Patent is hereby corrected as shown below:

Delete "FIG. 3 is a front elevation view of the knob; and," and replace with
—FIG. 3 is a front elevation view of the knob.—

Signed and Sealed this

Fifteenth Day of May, 2001

Attest:

NICHOLAS P. GODICI
